US00D769909S

(12) **United States Design Patent** (10) **Patent No.:** **US D769,909 S**
Roberts et al. (45) **Date of Patent:** **** Oct. 25, 2016**

(54) **DISPLAY SCREEN OR PORTION THEREOF WITH GRAPHICAL USER INTERFACE**

(71) Applicant: **Apple Inc.**, Cupertino, CA (US)

(72) Inventors: **Samuel Morgan Roberts**, Santa Cruz, CA (US); **Randall Ubillos**, Los Altos, CA (US)

(73) Assignee: **Apple Inc.**, Cupertino, CA (US)

(**) Term: **15 Years**

(21) Appl. No.: **29/540,806**

(22) Filed: **Sep. 28, 2015**

Related U.S. Application Data

(63) Continuation of application No. 29/495,644, filed on Jul. 2, 2014, now Pat. No. Des. 745,564, which is a continuation of application No. 29/415,058, filed on Mar. 7, 2012, now Pat. No. Des. 710,381.

(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; FIG. 3 is a front view of a third embodiment thereof; FIG. 4 is a front view of a fourth embodiment thereof; and, FIG. 5 is a front view of a fifth embodiment thereof. The broken lines in the Figures show a display screen or portion thereof, and form no part of the claimed design.

1 Claim, 5 Drawing Sheets
